AUTOMOBILE GRILLE BAR

Henry T. King and Harold W. Pilkey, Detroit, Mich., assignors to Chrysler Corporation, Highland Park, Mich., a corporation of Delaware

Application July 22, 1954, Serial No. 31,534

Term of patent 7 years

(Cl. D14—18)

Fig. 1 is a perspective view of an automobile grille bar showing our new design, wherein the broken lines indicating a portion of an automobile are for illustrative purposes only;

Fig. 2 is a front elevational view of our automobile grille bar;

Fig. 3 is a fragmentary front elevational view of our automobile grille bar shown on a larger scale than that illustrated in Fig. 2;

Fig. 4 is a top plan view of the device illustrated in Fig. 3;

Fig. 5 is an end elevational view thereof;

Figs. 6 and 7 are sectional views taken on the lines 6-6 and 7-7 respectively of Fig. 3; and

Figs. 8 and 9 are sectional views taken on the lines 8-8 and 9-9 respectively of Fig. 5.

The characteristic features of our design reside in the portions shown by means of full lines in the drawings.

We claim:

The ornamental design for an automobile grille bar, substantially as shown and described.
